UNITED STATES PATENT OFFICE.

CHARLES HERTLE, OF ASTORIA, NEW YORK.

TOOL-MAKER'S CLAMP.

1,286,314.

Specification of Letters Patent.

Patented Dec. 3, 1918.

Application filed March 7, 1918. Serial No. 220,896.

To all whom it may concern:

Be it known that I, CHARLES HERTLE, a subject of the Emperor of Austria-Hungary, residing at Astoria, in the county of Queens 5 and State of New York, have invented certain new and useful Improvements in Tool-Makers' Clamps, of which the following is a specification.

The present invention relates to tool 10 maker's clamps which are generally used for clamping a number of pieces together for drilling purposes or other operations thereon.

Clamps of this type are usually constructed 15 of two parallel jaws connected together by parallel screws so that by holding the heads of the screws one with each hand and swinging the jaws around one of the screws as on an axis, the jaws will close or open.

With the hitherto used construction of 20 such clamps there is the drawback that one of the jaws which is not engaged by the threads of the screws has the tendency, during the closing and opening of the clamp, to drop or slide, which renders the clamp temporarily inoperative.

The object of my invention is to obviate 25 this drawback by providing a construction in which the said jaw will always be held in a stationary position.

Another object of my invention is to so construct the device that the means for the purpose set forth will be concealed within the jaw and thereby prevented from disarrangement or damage, rendering the clamp 30 durable and inexpensive.

With these objects in view, my invention consists in the construction, combination and arrangement of parts as will be herein- 35 after more fully described and set forth in the appended claims.

In the accompanying drawing similar reference characters denote corresponding parts and Figure 1 is an elevation of the 40 clamp; Fig. 2 an enlarged section on line 2-2 of Fig. 1; Fig. 3 a cross section on line 3-3 of Fig. 2; Fig. 4 a cross section on line 4-4 of Fig. 2 and Fig. 5 is a similar section as Fig. 2 showing the stationary jaw as 45 being partly in engagement with the screw before these parts are permanently locked.

In the drawing *a, b* denote the jaws of the 50 clamp of the usual shape and *c, d* the two parallel screws having heads *c', d'* respectively on the outer sides of the jaws. The

jaw *a* is provided with two parallel threaded bores *a', a''* in which work respectively the screws *c, d*. The jaw *b* has in its inner or clamping surface a socket or groove *b²* in which freely or rotatively bears the reduced 60 end *c²* of the screw *c*. It also has near its other end a cylindrical bore *b⁵* which in diameter is about equal to or slightly larger than that of the threaded portion of the screw *d* so that the latter will freely pass 65 therethrough and its unthreaded part *d²* will rotatively bear within said bore. Now in order to prevent the jaw *b* from dropping or slipping down the screw *d* during the 70 swinging of the jaws for their adjustment into the proper clamping position, I provide the following construction:

The screw *d* is provided on its unthreaded portion *d²* with an annular groove *d³*. In the bore *b⁵* of the jaw, a groove *b³* is provided which extends longitudinally from the outer open end thereof to an intermediate point which coincides with the lower edge of the annular groove *d³* of the screw 75 when the latter is in normal position. This groove *b³* is of uniform semicircular cross section throughout its length excepting at its lower end beginning from the upper edge of the annular groove *d³* where it is enlarged by milling a groove *b⁴* whose depth opposite 80 the annular groove *d³* is a small fraction of an inch larger than that of the bore *b³*. The excess depth is smaller than the depth of the annular groove *d³*. A ball *e*, which in diameter is equal to the total depth of the bore *b⁵* and the annular groove *d³*, serves to 85

lock the screw *d* and the jaw *b* together. This locking will take place upon the entry of the ball *e* into the enlarged part of the groove *b⁴*. With the ball *e* located in the 90 annular groove *d³* of the screw *d*, the latter can be passed through the bore *b⁵*, the projecting part of the ball fitting in the groove *b³*. When the ball arrives opposite the enlarged part *b⁴* of the groove, it will receive 95 play which will permit it to become displaced relative to the groove *d³* and bore *b³* and lock the screw within the jaw. The upper or lower edge of the annular groove *d³* will, on the attempt to separate the parts, 100 exert a lateral pressure on the ball and thrust the latter sidewise so that the escape of the ball through the groove *b³* will not be possible.

Although a very simple means, yet this 110

lock has proved to be very effective and to considerably improve the construction of this type of clamps.

What I claim and desire to secure by Letters Patent is:

1. A ball controlled joint consisting of one member having a bore formed with a longitudinal groove extending from its open end to an intermediate point of said member and 10 enlarged at said point, and another member having an annular groove adapted when the members are in normal engagement to coincide with said enlarged portion of said longitudinal groove, and a ball engaging said 15 annular groove and adapted when so engaged to snugly fit in said longitudinal groove and on its entry into the widened portion of the latter to permanently lock the two members together.
2. A clamp comprising parallel jaws and 20

screws connecting the same, one of said jaws having a bore formed with a longitudinal groove extending from its open end to an intermediate point thereof and one of said screws having an annular groove adapted 25 when in normal engagement with said last named jaw to coincide with the enlarged portion of said longitudinal groove and a ball engaging said annular groove and adapted when so engaged to snugly fit in 30 said longitudinal groove and on its entry into the widened portion of the latter to permanently lock said screw to said jaw.

In testimony whereof I affix my signature in presence of two witnesses.

CHARLES HERTLE.

Witnesses:

FRED. J. GRIESMER,
ELSIE SCHMID.
